UNITED STATES PATENT OFFICE.

JOHN D. MERRIFIELD, OF ERIE, PENNSYLVANIA, ASSIGNOR TO REED MANUFACTURING COMPANY, OF ERIE, PENNSYLVANIA, A CORPORATION OF PENNSYLVANIA.

PIPE CUTTER.

Application filed February 19, 1923. Serial No. 619,882.

This invention is designed to improve the construction of pipe cutters. With such cutters the shanks are subjected to very severe torsional strains and the present invention makes a more rigid shank than that now ordinarily employed. At the same time the construction lends itself to convenience of manufacture with relation to other parts of the structure. Further features and details will appear from the specification and claim.

The invention is illustrated in the accompanying drawings as follows:

Fig. 1 shows a central section through the cutter,

Fig. 2 a section on the line 2—2 in Fig. 1, and

Fig. 3 a side elevation of the cutter.

1 marks the shank, 2 the nose extending from the shank, 3 a sliding cutter head, and 4 a socket in the sliding head for receiving the head 5 of the screw 6. A screw 7 locks the head 5 in the socket 4. The screw 6 extends through a nut 8 and the end of the screw is provided with a handle 9.

The nut has a tenon 10 which extends through a transverse opening 11 in the shank 1 and the end of this tenon is headed down at 12, thus securing the nut on the shank.

The shank is rectangular in cross section with top and bottom walls 13 and side walls 14, the shank having a longitudinal opening

15 within these walls. These walls and this opening are continued into the nose 2, the opening being extended by way of a slot 16 through the inner face of the nose. This manner of forming the opening is of particular advantage in the manufacture in that the opening 15 may be readily cored and the core supported through the slot 16. At the same time the slot 16 forms an opening for receiving the cutter wheels 17 which are arranged within this slot and mounted in the nose. The usual cutter 3^a is mounted on the head 3.

What I claim as new is:

In a pipe cutter, the combination of a shank of rectangular cross-section having integral top, bottom and side walls with a longitudinal cavity within the walls; a cutter head slidingly mounted on the shank; a nose extending from the shank and having a slot opening on the inner surface of the nose, said slot communicating with the opening in the shank and forming a means of communication to the opening through which a core forming the opening may be supported; and cutter wheels arranged in the slot and mounted in the nose.

In testimony whereof I have hereunto set my hand.

JOHN D. MERRIFIELD.
